BY

Richard Oliver.

ATTORNEY

UNITED STATES PATENT OFFICE.

WARD JOHN TOLAND, OF DANNEMORA, NEW YORK.

DIRECTORY.

1,346,995.

Specification of Letters Patent. Patented July 20, 1920.

Application filed December 5, 1918. Serial No. 265,375.

To all whom it may concern:

Be it known that I, WARD J. TOLAND, a citizen of the United States, residing at Dannemora, in the county of Clinton and State of New York, have invented certain new and useful Improvements in Directories, of which the following is a specification.

This invention relates to a directory, and 10 more particularly to a device in which words or names may be printed on belts or strips which are moved across observation openings.

One of the main objects of the invention 15 is to provide a directory of the character stated of simple construction and operation employing a plurality of independent units each provided with a strip or belt of material on one face of which may be inscribed 20 suitable words, names or other symbols. A further object is to provide means for operating the endless strips or belts so as to maintain the same at constant tension when moved toward the observation. Another object 25 is to provide simple and efficient means for holding the units of the directory in operative position so as to permit ready removal thereof. Further objects will appear 30 from the detailed description.

In the drawings:

Figure 1 is a top plan view of a directory constructed in accordance with my invention,

Fig. 2 is a fragmentary detail sectional 35 view taken through one of the units of the directory and the contiguous parts of the casing,

Fig. 3 is a fragmentary vertical sectional 40 view showing one of the units in operative position,

Fig. 4 is a fragmentary horizontal sectional view showing fragmentarily one of the units and the means for securing the same in position.

The box-like or rectangular casing 1 45 which may be formed of sheet metal or any other suitable material, is adapted to be supported by a suitable wooden base 2. This casing is provided, at its transverse center, 50 with a longitudinally extending partition member 3 which extends the full length of the casing. In this manner, the interior of the casing is divided into two equal longitudinally extending compartments. The 55 top 4 of the casing is provided with two longitudinally extending series of transversely

extending spaced openings 5 which communicate with the respective compartments of the casing. A suitable closure member or panel 6 of glass or other suitable transparent material is supported closely adjacent the under face of top 4 of the casing at each side of the partition member 3. In this manner, entry of dust or foreign material into the casing is prevented while the 60 symbols marked on the belt of the indicating unit to be later described may be readily observed through the observation opening 5.

Partition member 3 is provided on each lateral face with a plurality of spaced substantially U-shaped guide strips 7. These strips serve to provide vertically extending guide grooves which snugly receive the inner end plates 8 of the indicating units 70 designated generally by 9. Each of the units 9 is provided with an inner plate 8, which is adapted to fit snugly between the guide members 7 and an outer end plate 10. These end plates are secured in parallel spaced 75 relation by the spacing rods 11 secured thereto. The upper spacing rods are provided with sleeve rollers 12 loosely mounted thereon so as to form anti-friction bearing members for a strip or belt 13 of fabric 80 or other suitable material which is movable over the same. When the units are in position, they are so spaced that the horizontal run of the belt is positioned immediately below one of the observation openings 5 so 85 that the symbols which are marked on the outer face of the belt are thus rendered readily visible.

Belt 13 is wound on a spool or roller 14 90 which is rotatably supported upon a shaft 95 15 in the end plates 9 and 10. Roller 14 is in vertical alinement with a similar roller 16 rotatably supported, by means of a shaft 17 to which the roller is secured, in the end plates. The belt 13 after being wound upon 100 roller 14 is passed over the sleeve rollers 12 and downwardly in front of roller 14 between the two rollers, being then wound in the opposite direction upon roller 16.

To permit roller 14 to be turned from 105 without the casing 1, shaft 15 projects beyond the outer end plate 10 and the end portion of this shaft is squared, as at 20. This squared portion is adapted to fit snugly into a corresponding bore 21 provided in neck 110 22 of a thumb knob 23. The neck of this knob is adapted to be inserted through an

opening 24 provided in the outer wall of the casing 1 for this purpose. The neck or shank 22 is provided with an opening which accommodates the angularly bent portion 25 of a securing spring 26 which frictionally engages into a corresponding recess in the squared portion 20 of shaft 15 so as to frictionally secure the thumb knob 23 thereto. In this manner, after the unit has been placed in position, the thumb knobs may be readily secured thereto for operating purposes.

In Fig. 5 a conventional compensating means is shown whereby the roller 14 is rotatably mounted upon the shaft 15 and is connected thereto by means of a compensating spring 30. This compensating spring 30 fits in a pocket provided in the roller 14 adjacent the wheel 18. The spring 30 has one end attached to the shaft 15 by means of the pin 31 and its other end attached to the roller 14. By means of the compensating means the difference in diameter of the rolls will be compensated for by the winding or unwinding of the spring 30.

In practice, as many of these units may be employed as described, each belt or strip containing the words which commence with a particular letter and being positioned beneath the observation opening 5 bearing the designation or letter corresponding to the letter with which the words on the particular belt commence. To render the words or the symbols on the various belts readily visible through the openings 5, the top of the casing is inclined and the units 9 are arranged in stepped order, as in Fig. 2. This permits the words of the units at the upper or top end of the casing to be readily viewed through the observation openings, as will be obvious. This device is well adapted for use as a directory, each strip or belt containing the names beginning with some particular letter, or it may be used as a dictionary or for similar purposes. The symbols or words which are printed upon the belt may be readily moved across the observation opening, until the desired name or word is exposed. This greatly facilitates finding of the particular word or name desired and avoids the necessitating of turning a number of pages in an attempt to locate a name or word such as is necessary in using a directory or dictionary of ordinary construction.

The foregoing description and the draw-

ings have reference to what may be considered the preferred, or approved form of invention. It is to be understood that I may make such changes in construction, and arrangement and combination of parts, materials, dimensions, etc., as may prove expedient and fall within the scope of the appended claims.

Having thus fully described my invention, what I claim as new and desire to secure by Letters Patent, is:

1. In a device of the class described, the combination of a casing having guide strips therein, independent indicating units insertible in said casing and comprising plates connected by rods, shafts carried by said plates and having rollers thereon, sleeve rollers carried by a plurality of said rods, a belt connected to said rollers and passing around said sleeve, rollers, said plates being engaged by said strips for holding said units against accidental shifting although permitting the same to be removed from the casing when necessary, and means insertible into said casing for engagement with said shafts and turning the same whereby said rollers may be rotated for moving said belt.

2. In a device of the class described, the combination of a casing, independent indicating units insertible into and removable from said casing, each including a plurality of rollers having a belt connected thereto, shafts supporting said rollers, said shafts having squared ends, said casing having openings in the sides thereof, a neck having a squared bore at one end and a knob at the opposite end thereof insertible through each opening, said necks engaging said shafts, said shafts having recesses in their squared ends, springs fixed upon said necks and having angularly bent portions fitting within said recesses thus releasably connecting said necks to said shafts, whereby when said knobs are turned, rotary motion will be imparted through said necks to said shafts although when it is desired to remove an indicating unit the knobs thereof may be moved from engagement with the shafts, whereby the indicating unit may be easily lifted from the said casing.

In testimony whereof I affix my signature in presence of two witnesses.

WARD JOHN TOLAND.
